WEDGE-TYPE CLAMP AND CARRIER BAR

James P. Ratigan, Los Angeles, Calif.

Application September 20, 1941, Serial No. 411,674

15 Claims. (Cl. 24—263)

My invention relates to a clamp for reciprocating rods and has particular reference to a wedge-type clamp which may be employed either as a carrier bar or as a spacing clamp in oil well pumping installations.

It is the present practice to effect the driving connection between the oscillating walking beam and the polished rod of an oil well pumping installation by means of a horsehead sling which usually comprises a pair of rods or cables depending from the end of the walking beam which are pivotally connected to trunnion portions of a carrier bar attached to the polished rod.

While the present practice is to employ a carrier bar which loosely encircles the polished rod and so requires the employment of a separate polished rod grip disposed above the carrier bar, it has also been suggested that the carrier bar and grip be combined in a single structure. I have, for example, disclosed in my copending application, Serial No. 411,043, filed September 16, 1941, now Patent No. 2,296,182, granted September 15, 1942, and entitled Clamp type carrier bar, a very practical form of such a combination device. However, no one prior to this present invention has suggested employing such a combination device in which a wedge-type clamp mechanism is used to secure the device to the polished rod, although wedge-type clamps designed for other uses are well known and despite the fact that it has been long recognized that wedge-type clamps provide a clamping action which is superior to the bolted types of clamps. This is perhaps due to the difficulty of providing a device which is properly balanced.

Clamp-type carrier bars must be balanced. That is, the axis of the trunnions must pass through the axis of the polished rod and the weight of the device should also be uniformly distributed on opposite sides of the trunnion axis. If the device is unbalanced, the pumping operation imposes undesired bending stresses on the polished rod resulting in undue wear of the stuffing box and early failure of the polished rod through wear and fatigue.

It is, therefore, an object of my invention to provide a clamp device which may serve as a combined polished rod grip and carrier bar and which employs a wedge-type clamping mechanism, the device being so designed that the trunnion axis intersects the axis of the polished rod.

It is also an object of my invention to provide a clamp of the character set forth in the preceding paragraph in which the weight of the

device is balanced on opposite sides of the trunnion axis.

It is a still further object of my invention to provide a clamp of the character previously referred to in which means is employed for permanently securing the wedging members to the device while permitting movement of such members to effect a clamping and an unclamping operation, thereby avoiding the danger of the wedging members being lost.

It is an additional object of my invention to provide a device of the character set forth in the preceding paragraphs in which a self-equalizing gripping means is employed to engage the polished rod, the gripping means being actuated by a wedging mechanism.

It is also an object of my invention to provide a device of the character hereinbefore referred to which is of strong and rugged construction affording a grip on the polished rod which is equal to or greater than that obtainable with bolted clamps.

Other objects and advantages of my invention will be apparent from a study of the following specifications, read in connection with the accompanying drawings, wherein:

Fig. 1 is a perspective view illustrating the construction of the preferred form of my invention and the manner in which it is employed when functioning as a combined polished rod grip and carrier bar;

Fig. 2 is a top plan view of the device illustrated in Fig. 1;

Fig. 3 is a vertical sectional view taken substantially along the line III—III of Fig. 2;

Fig. 4 is a horizontal sectional view taken substantially along the line IV—IV of Fig. 1 and illustrating the relative positions of the parts when the device is clamped to a polished rod; and

Fig. 5 is a view similar to Fig. 4 but illustrating the manner in which the parts may be moved to positions permitting the removal of the polished rod from the clamp or the attachment of the clamp to the polished rod.

Referring to the drawings, I have illustrated the preferred embodiment of my invention as comprising a combined polished rod grip and carrier bar 1 which may be employed in an oil well pumping installation to effect a driving connection between the walking beam and the polished rod. In Fig. 1 a section of the polished rod is identified by reference character 2 and to this polished rod the carrier bar 1 is secured. The carrier bar 1 includes trunnion portions 3

and 4 which extend laterally outward from the polished rod 2 and afford a pivotal connection to horsehead sling cables 5 and 6 through the medium of eye members 7 and 8. The horsehead sling cables 5 and 6 extend upwardly into connection with the walking beam (not shown) so that the vertical reciprocation of the cables 5 and 6 serves to likewise reciprocate the polished rod 2.

The carrier bar 1 preferably comprises a body portion 9 which is preferably of a roughly rectangular shape as viewed both in plan and in elevation. The body member 9 is provided with a vertically extending slot 10 having a width sufficient to loosely receive the polished rod 2, the innermost end of the slot 10 being provided with a seating surface 11 (see Fig. 5) having a curvature closely conforming to the curvature of the polished rod 2 and providing an abutment against which the polished rod 2 may be clamped.

The securing of the body member 9 to the polished rod is effected by means of a pair of gripping elements 12, one of which is illustrated in Figs. 4 and 5. Each of the gripping elements 12 comprises block-like members, the inner face of which is grooved as indicated at 13 to match up with the seating surface 11 and in association therewith to encircle the polished rod 2. The opposite face of the member 12 preferably comprises a plane surface 14 against which one side 15 of a tapered wedging member 16 may bear. A separate wedging member 16 is employed for each of the gripping elements 12 and each of the members 16 are passed laterally through the body portion 9 of the device in such direction as to extend across the rod receiving slot 10, the body 10 being laterally slotted as indicated at 17 and 18 in Figs. 1 and 5 to receive the wedging members 16. The slots for the wedging members define outwardly positioned and inwardly facing pressure surfaces 19 and 20 adapted to engage the edge 21 of the wedging members disposed opposite the edge surfaces 15.

It will be noted that as the wedging members 16 are moved inwardly or from the position illustrated in Fig. 5 to that illustrated in Fig. 4, the wedging action produced by the tapered sides 15 and 21 against the surfaces 14, 19 and 20 will serve to urge the gripping member 12 toward the polished rod 2 with a tremendous force.

The wedging members 16 are preferably permanently associated with the body member 9 and are for this purpose provided with longitudinally extending grooves 22 which are formed in one surface of the members 16. The grooves 22 receive projections 23 which are formed on the body member 9 and extend into the slots 17-18.

In manufacturing the device, the groove 22 is preferably extended completely into one end of the wedging member such as the innermost end indicated by reference character 24. This permits the wedging member to be inserted into the slot 17-18 to a position such as that illustrated in Fig. 4. Thereafter the end of the groove 22 is welded full as by means of a weld 25. This weld then prevents subsequent disassociation of the wedging member from the rest of the device since outward movement of the wedging member is arrested by engagement of the projection 23 with the weld 25.

Each of the gripping members 12 is preferably likewise permanently associated with the device and each of the members 12, therefore, includes a curved tailpiece 26 which is enlarged as indicated at 27 and provided with a vertically ex-

tending opening 28 through which a pin 29 is extended, the pin 29 being suitably permanently secured to the body 9 as by welding or riveting. By forming the opening 28 of a size materially larger than the size of the pin 29, a considerable latitude of movement is afforded the corresponding members 12, thus permitting these members to assume that position in which their rod engaging surfaces 13 are properly aligned and seated upon the face of the rod. When clamping pressure is exerted on the rod 2 by driving the wedge members 16 inwardly, distortion of the rod is avoided because of the provision which is made to allow the gripping members 12 to move to such positions as to equalize the load on all of the engaged surfaces of the polished rod.

It is preferred that the swinging movement of the gripping members 16 which is permitted by the pivotal connection of these members to the body member 9 be limited substantially to the positions illustrated in Figs. 4 and 5, the position illustrated in Fig. 5 being that which will just permit the polished rod 2 to be passed inwardly along the slot 10. For this purpose a projection 30 is formed on the tailpiece 26, the projection 30 being of such form and shape as to engage one of the vertical surfaces 31 defined by the slotting of the body member 9 when the member 12 is moved to the position illustrated in Fig. 4. It will have been noted that the slots 17-18 which are provided for the wedging members 16 are made with a sufficient lateral scope to not only receive the wedging members 16, but to provide space also for housing the gripping members 12 and the pivotal connections therefor comprising the tailpiece 26 and pivot pin 29.

While I have described the wedge-type clamping mechanism which is employed on the carrier bar 1 as including a pair of wedging members 16 and a corresponding pair of the gripping elements 12, it will be understood that the device may, if desired, be provided with but a single wedging member and a single gripping member or, conversely, if it is desired to exert extremely large clamping forces on the polished rod 2, the device may include more than two of the wedging members and gripping elements.

The trunnion portions 3 and 4 previously referred to are preferably formed integrally with the body member 9 and are so positioned on the body member 9 that their longitudinal axes will extend at right angles to and intersect the axis of the polished rod 2 when the polished rod 2 is seated in its seat 11. These trunnions are preferably of substantially circular cross section providing for the reception into the eye members 7 and 8 and may also be provided with laterally extending apertures 32 into which keeper pins 33 may be inserted after the trunnions are placed in the eye members 7 and 8, the keeper pins serving to prevent inadvertent removal of the trunnion members from the eye members. Additional strength may be built into the device by employing a buttress type of bracing 34 extended between the body member 9 and the under side of the trunnion members. Preferably the amount of inward movement which is permitted the eye members 7 and 8 is limited in the case of the eye member 7 by its engagement with the downwardly extending portion of the body member 9 indicated by reference character 35 in Fig. 1, and in the case of the eye member 8 by a suitable shoulder or abutment 36 which is formed integrally with the trunnion member 4 and which surrounds the same.

Reference has been made hereinbefore to the desirability of maintaining a uniform distribution of the weight of the device on opposite sides of the axis of the trunnion members 3 and 4. I have attained this object by extending the slot 10 in a direction which is nearly parallel to the axis of the trunnions 3 and 4, the slot 10 being disposed at a sufficient angle to extend outwardly from the trunnion axis a distance equal to half its width in its entire length. Reference to Fig. 2 will disclose that this construction disposes equal amounts of metal on opposite sides of the axis of the trunnion portions 3 and 4 and also provides for the disposition of half of each of the wedging members 16 on opposite sides of the trunnion axis when these members are in their clamping position such as is illustrated in Fig. 2.

While I have described the preferred embodiment of my invention as being adapted particularly for use as a combined polished rod grip and carrier bar, attention is directed to the fact that if desired the trunnion portions 3 and 4 may be omitted, in which event the device may be employed as a spacer clamp. In oil well pumping practice such clamps are secured to the polished rod in a position engaging the stuffing box so that the entire weight of the sucker rod string which is attached to the polished rod may be supported thereby while the horsehead connection to the upper end of the polished rod is disassociated as for repairs or for the purpose of changing the location of the carrier bar to change the limits of the pump stroke.

The device which I have illustrated herein may also be used as a spacing clamp, in which event the trunnion portions 3 and 4 serve as convenient handles by which the device may be lifted and placed around the polished rod.

In attaching the clamp device of my invention to the polished rod the parts are first moved to the positions illustrated in Fig. 5 and the device is so moved as to cause the polished rod 2 to pass inwardly along the slot 10 and be seated against the polished rod seat 11. Thereafter the gripping members 12 are swung from the positions illustrated in Fig. 5 to the positions illustrated in Fig. 4, whereupon the wedging members 16 will be moved inwardly from their Fig. 5 position to their Fig. 4 position. Thereafter the wedges may be tightened as by striking the same with a hammer on their end faces 37.

It will be appreciated that by making the taper on the wedging faces 15 and 21 of a slight angularity tremendous clamping forces may be developed without requiring excessively violent blows to be struck. I have, for example, discovered by test that a clamp of the character illustrated in Fig. 1 will, when secured to a standard polished rod by employing a hammer no heavier than three pounds for driving the wedges home, stand a pull of at least 53,000 pounds.

The device may be readily removed from the polished rod by reversing the above described operation, the wedges 16 being preliminarily loosened by striking the inner ends 24 with a hammer.

From the foregoing it will be observed that I have provided a novel clamp for reciprocating rods which may be used either as a spacing clamp or as a combined polished rod grip and carrier bar, as desired.

Attention is directed to the fact that my invention permits the axis of the trunnions 3 and 4 to intersect the axis of the polished rod 2 and

that by arranging the parts in accordance with my invention the weight of the device may be substantially uniformly disposed on opposite sides of the trunnion axis.

Attention is also directed to the fact that the provision of the self-equalizing gripping elements 12 prevents injury to the polished rod resulting either from the application of non-uniformly distributed clamping forces or resulting from the engagement of the wedging members themselves with the surface of the polished rod.

It will be noted that all of the movable parts of the device are permanently associated with the device so that it is impossible for the device of my invention to become inoperative or useless through the inadvertent loss of the wedging members or the gripping elements.

While I have shown and described the preferred embodiment of my invention, I do not desire to be limited to any of the details of construction shown or described herein, except as defined in the appended claims.

I claim:

1. In a clamp for attachment to a rod, the combination of: a body member having a rod receiving slot extending into one side thereof; a gripping member pivotally supported on said body member for movement from a position away from said slot to a position extending thereacross, said gripping member having a rod engaging surface and an opposite surface so directed as to extend transversely of said slot when said rod engaging surface is engaged with said rod; a tapered wedging member supported on said body member for movement transversely of said slot with one wedging surface engaging said opposite surface of said gripping member; and means on said body member for engaging the other wedging surface of said wedging member.

2. In a clamp for attachment to a rod, the combination of: a body member having a rod receiving slot extending into one side thereof and defining at its innermost end a seating surface conforming in contour to the surface contour of said rod; a gripping member pivotally supported on said body member for movement from a position away from said slot to a position extending thereacross, said gripping member having a rod engaging surface contoured to conform to the surface contour of said rod and having an opposite surface so directed as to extend across said slot when said rod engaging surface is engaged with said rod; a tapered wedging member supported on said body member for movement transversely of said slot with one wedging surface engaging said opposite surface of said gripping member; and means on said body member for engaging the other wedging surface of said wedging member.

3. In a clamp for attachment to a rod, the combination of: a body member having a rod receiving slot extending into one side thereof; a gripping member mounted on said body member having a rod engaging surface and an opposite surface so directed as to extend transversely of said slot when said rod engaging surface is engaged with said rod; pivot means on said body member; means on said gripping member defining an opening for receiving said pivot means to mount said gripping member on said body member for pivotal movement from a position away from said slot to a position extending thereacross, said opening being sufficiently large to loosely receive said pivot means and permit limited translatory movement of said gripping member.

70 4. In a clamp for attachment to a rod, the combination of: a body member having a rod receiving slot extending into one side thereof; a gripping member having a rod engaging surface and an opposite surface so directed as to extend transversely of said slot when said rod engaging surface is engaged with said rod; pivot means on said body member; means on said gripping member defining an opening for receiving said pivot means to mount said gripping member on said body member for pivotal movement from a position away from said slot to a position extending thereacross, said opening being sufficiently large to loosely receive said pivot means and permit limited translatory movement of said gripping member.

toward and away from said rod; and wedging means carried by said body member and engageable with said opposite surface of said gripping member to forcibly move said gripping member toward said rod.

4. In a clamp for attachment to a rod, the combination of: a body member having a rod receiving slot extending into one side thereof and defining at its innermost end a seating surface conforming in contour to the surface contour of said rod; a gripping member mounted on said body member having a rod engaging surface contoured to conform to the surface contour of said rod and having an opposite surface so directed as to extend transversely of said slot when said rod engaging surface is engaged with said rod; pivot means on said body member; means on said gripping member defining an opening for receiving said pivot means to mount said gripping member on said body member for pivotal movement from a position away from said slot to a position extending thereacross, said opening being sufficiently large to loosely receive said pivot means and permit limited translatory movement of said gripping member in the direction of the length of said slot and transversely thereof to thereby allow said gripping member to assume a position in which said rod engaging surface thereof is aligned with the surface of said rod; and wedging means carried by said body member and engageable with said opposite surface of said gripping member to forcibly move said gripping member toward said rod.

5. In a clamp for attachment to a rod, the combination of: a body member having a rod receiving slot extending into one side thereof; a gripping member pivotally supported on said body member for movement from a position away from said slot to a position extending thereacross and engaging said rod; and wedging means carried by said body member and operable to engage said gripping member and force the same into pressure engagement with said rod.

6. In a clamp for attachment to a rod, the combination of: a body member having a slot extended thereinto from one side for receiving said rod; a wedging means; and mounting means permanently securing said wedging means to said body member, said mounting means being so constructed and arranged as to permit limited movement of said wedging means from a position extending across said slot and locking said rod therein to a position away from said slot permitting movement of said rod therefrom.

7. In a clamp for attachment to a rod, the combination of: a body member having a slot extending thereinto from one side for receiving said rod and having a wedge receiving opening extending across and intersecting said slot; a tapered wedging member slidably received in said opening for limited movement from a position extending across said slot and locking said rod therein to a position out of said slot permitting movement of said rod therefrom; and means permanently attaching said wedging member to said body member.

8. In a clamp for attachment to a rod, the combination of: a body member having a slot extending thereinto from one side for receiving said rod and having a wedge receiving opening extending across and intersecting said slot; a tapered wedging member slidably received in said opening for limited movement from a position extending across said slot and locking said rod

therein to a position out of said slot permitting movement of said rod therefrom, said wedging member having a longitudinally extending groove formed in one side thereof and terminating short of both ends of said wedging member; and a projection on said body member extending into said opening and into said groove.

9. In a clamp for attachment to a rod, the combination of: a body member having a pair of aligned trunnion members formed integrally therewith and extending horizontally outward from opposite sides thereof, said body member having a vertical rod receiving slot extended horizontally into said body member from one side thereof and terminating in a vertical rod engaging surface so positioned that the axis of a rod engaging said surface will intersect the axis of said trunnion members, the location of said slot being such that its depth is disposed at a slight angle to the axis of said trunnion members; and wedging means carried by said body member for clamping said rod against said rod engaging surface.

10. In a deep well pumping apparatus including a power driven oscillating member and a sucker rod extending into said well, the combination of: a body member having a rod receiving slot extending into one side thereof; a gripping member pivotally supported on said body member for movement from a position away from said slot to a position extending thereacross and engaging said rod; wedging means carried by said body member and operable to engage said gripping member and force the same into pressure engagement with said rod; and means on said body member for drivably interconnecting said body member with said oscillating member.

11. In a clamp for attachment to a rod, the combination of: a substantially U-shaped body member including a pair of spaced arms defining a rod receiving slot having one end closed; a pair of aligned trunnion members carried by said body member, one extending outwardly from the end of one of said arms of said U-shape and the other extending in an opposite direction from the bottom of said U-shape; a pressure block mounted on said body for movement to a position engaging said rod and forcing the same into the closed end of said slot; and wedge means on said body for so moving said pressure block.

12. In a clamp for attachment to a rod to be reciprocated by an oscillating power means, the combination of: a substantially U-shaped body including a pair of spaced arms defining a rod receiving slot having one end closed; means for effecting a connection of said body with said oscillating power means, said means including members secured to one arm of said U-shape and to the bottom of said U-shape; a pressure block mounted on said body for movement to a position engaging said rod and forcing the same into the closed end of said slot; and wedge means on said body for so moving said pressure block.

13. In a clamp for attachment to a rod to be reciprocated by an oscillating power means, the combination of: a body member having a rod receiving slot extending into one side thereof; suspension means on said body member for connecting said body member to said oscillating power means, the depth of said slot being such that the axis of a rod engaging the bottom thereof will intersect the axis of said suspension means; a gripping member pivotally supported on said body member for movement from a position

away from said slot to a position extending thereacross, said gripping member having a rod engaging surface and an opposite surface so directed as to extend transversely of said slot when said rod engaging surface is engaged with said rod; a tapered wedging member supported on said body member for movement transversely of said slot with one wedging surface engaging said opposite surface of said gripping member; and means on said body member for engaging the other wedging surface of said wedging member.

14. In a clamp for attachment to a rod to be reciprocated by an oscillating power means, the combination of: a body member having a rod receiving slot extending into one side thereof; suspension means on said body member for connecting said body member to said oscillating power means, the depth of said slot being such that the axis of a rod engaging the bottom thereof will intersect the axis of said suspension means; a gripping member mounted on said body member having a rod engaging surface and an opposite surface so directed as to extend transversely of said slot when said rod engaging surface is engaged with said rod; pivot means on said body member; means on said gripping member defining an opening for receiving said pivot means to mount said gripping member on said body member for pivotal movement from a posi-

tion away from said slot to a position extending thereacross, said opening being sufficiently large to loosely receive said pivot means and permit limited translatory movement of said gripping member toward and away from said rod; and wedging means carried by said body member and engageable with said opposite surface of said gripping member to forcibly move said gripping member toward said rod.

- 10 15. In a clamp for attachment to a rod to be reciprocated by an oscillating power means, the combination of: a body member having a slot extended thereinto from one side for receiving said rod; suspension means on said body member for connecting said body member to said oscillating power means, the depth of said slot being such that the axis of a rod engaging the bottom thereof will intersect the axis of said suspension means; a wedging means; and 15 20 mounting means permanently securing said wedging means to said body member, said mounting means being so constructed and arranged as to permit limited movement of said wedging means from a position extending across said slot and locking said rod therein to a position away from said slot permitting movement of said rod therefrom.

JAMES P. RATIGAN.
